Machine for Corrugating Nails.

No. 240,702.

Patented April 26, 1881.

UNITED STATES PATENT OFFICE.

HAYWARD A. HARVEY, OF ORANGE, NEW JERSEY.

MACHINE FOR CORRUGATING NAILS.

SPECIFICATION forming part of Letters Patent No. 240,702, dated April 26, 1881.

Application filed October 20, 1880. (No model.)

To all whom it may concern:

Be it known that I, HAYWARD A. HARVEY, of Orange, in the county of Essex and State of New Jersey, have invented certain new and useful Improvements in Machines for Corrugating Nails, of which the following is a specification.

The object of my improvements is to provide an effective and convenient machine for forming circumferential corrugations upon the bodies of nails, and particularly the kind of nails known as "French nails."

To this end my improvements consist in the combination with a rocking delivery-hopper, having a pivotal support, of a brush rotating in said hopper and pulleys or wheels, one upon the shaft on which the brush is journaled for driving said shaft and brush, and one coincident with the pivotal support of said hopper, whereby the nails in the hopper are prevented from crowding too forcibly against those being delivered from the hopper.

They also consist in the combination, with corrugating-dies and ways or tracks whereby the nails to be corrugated are conveyed toward the corrugating-dies, of a curved chute for conveying the nails from the ways or tracks toward the corrugating-dies and properly presenting them for entrance between the corrugating-dies.

In the accompanying drawings, Figure 1 is a front view of a machine embodying my improvements. Fig. 2 is a view of one side of the same. Fig. 3 is a view of the other side of the same. Fig. 4 is a transverse section of the delivery-hopper of the machine. Fig. 5 is an end or front view of the corrugating-dies and a dotted outline of the tracks or ways and the curved tube or chute. Fig. 6 is a detail view including a longitudinal section of a portion of the tracks or ways, and of the curved chute, and a side or face view of the corrugating-dies; and Fig. 7 is a plan of the corrugating-dies, the tracks or ways, the curved tube or chute, and other parts taken on a plane parallel with the axis of one of the corrugating-dies.

Similar letters of reference designate corresponding parts in all the figures.

A B designate the corrugating-dies (see particularly Fig. 5,) consisting, respectively, of a roll and segmental block, having their adja-

cent faces grooved or provided with ridges, whereby corrugations will be formed on the bodies of nails rolled between them. The nails to be corrugated are fed in at the upper end 55 of the segmental block with their bodies between said block and the roll and their heads outside, and they are delivered from the lower end of the said block.

The roll A is supported on a rotary shaft, 60 C, and the block B is preferably made adjustable, to cause the grooves or ridges on the block to converge more or less toward those of the roll from the upper to the lower end of said block, and thereby effect the corruga- 65 tion of the nails gradually in their transit. As here shown, the said block is supported, about midway between its ends, by a stud, D, and is adjusted by means of rotary pins or studs E, provided with cams E', bearing 70 against the exterior of the block, near its ends, the said pins or studs E being turned or rotated, by a wrench or otherwise, to cause the cam of either to force the adjacent portion of the block nearer to the roll. 75

The shaft C, carrying the roll A, is mounted in bearings erected on a bed, H, (shown as supported on a pillar, G') in an inclined position with the end adjacent to the said roll highest, wherefore the nails are not apt to fall 80 out from between the block B and the roll. The block B is supported on the end of the bed H adjacent to the said roll.

Having described the nature and operation of the corrugating-dies, I will proceed to de- 85 scribe the means whereby the nails to be corrugated are fed and presented to them.

F designates a delivery-hopper, wherein the nails to be corrugated are placed. They may be introduced directly into this hopper, or supplied in small quantities to it from a supplemental or supply hopper, G, mounted upon it. The hopper F is shown as pivoted at one end to a standard, F', so that it can be rocked up and down to facilitate the delivery of the nails 95 from it, and a rocking motion is imparted to it by means of a rod, F², connected to a wrist or crank, F³, on a wheel, F⁴, mounted on a counter-shaft, F⁵. This counter-shaft F⁵ is supported in an arm or bracket, F⁶, projecting 100 from the pillar G', and may be driven in any suitable manner. In the hopper F, along the

bottom, is a groove or opening in which the bodies of the nails hang while supported by their heads resting on the sides of the hopper adjacent to the groove. The nails thus supported travel through the groove toward the lower end of the hopper, and are delivered thence to inclined tracks or ways I, which support them by the heads while their bodies hang down between said tracks or ways. The nails slide down these tracks or ways to the lower end thereof, as seen by the nails S in Fig. 7. In the delivery-hopper F is a rotary-brush, J, of any suitable kind, supported on a shaft, J', so that at its lower portion it will brush or rub over the bottom of said hopper and against the nails which are in the hopper behind the brush but have not entered the groove therein. The shaft J' is driven by a crossed belt passing from the counter-shaft F⁵ to a pulley on a shaft, K, supported by the standard F', at the point where the delivery-hopper F is pivoted to it, and by a belt from another pulley on the same shaft to a pulley on the said shaft J', so that the lower portion of the brush J moves in the reverse direction to that in which the nails travel along the bottom of the delivery-hopper. The office of this brush is to force back the nails in the hopper which have not entered the groove therein, and to preclude them from crowding down on the nails in the said groove, and to throw them back, so that they may enter the groove. The nails, on arriving near the lower end of the tracks or ways I, are delivered into a curved tube or chute, L, under control of a check of any approved form. The check I have shown consists of two bars, M M', passing transversely through the tracks or ways I, connected by a bridge-piece, M², extending over said tracks or ways, and having a reciprocating motion imparted to them, whereby an inclined opening between their ends is intermittently brought opposite the opening between the tracks or ways, and allows the nails, one at a time, to pass between the bars. Owing to the opening between the bars being inclined, the nails are only allowed to move very slowly between them by gravitation, and hence are checked or precluded from passing too quickly and in too large quantities to the curved tube or chute L. To the check-bar M' is connected the upper end of a lever, N, pivoted at the lower end to the segmental or corrugating die B, and provided between its ends with an arm or lateral projection, N', carrying at its extremity a roller, N². On the adjacent end of the shaft C is a

wheel, C', provided with cam-like projections O², which, acting between the roller N² and a roller, M³, carried at the end of the adjacent check-bar M', impart a reciprocating motion 60 to the check-bars. The nails, after passing the check-bars M M', fall into the curved tube or chute L, as indicated by the nails S, in Fig. 6, and by said tube or chute are delivered in an approximately horizontal position upon the 65 top of the segmental block or corrugating-die B, with their heads outward, and they are thence pushed between said block and the roll A, whereupon the nails are operated upon by the block and roll. O designates a reciprocating delivery-slide, working over the top of the segmental block or corrugating-die B and pushing the nails, as they are delivered from the curved tube or chute L, into the space between the said block 75 and the roll A. This delivery-slide is connected to one arm of an elbow-lever, P, which is pivoted to a stud on the bed H, and is actuated by pins Q on the back of the wheel C', so as to impart the requisite reciprocating motion 80 to said delivery-slide. Preferably, the arm of the lever P, which is actuated by the pins Q, is jointed and has its two sections held in their proper relative positions by a spring, P', so that in case of any need the said arm may 85 bend back without operating the delivery-slide.

The shaft C of the machine may be driven in any suitable manner. I have shown it driven from a shaft, R, geared thereto and provided with suitable driving and idler pulleys. 90

What I claim as my invention, and desire to secure by Letters Patent, is—

1. The combination, with a rocking delivery-hopper having a pivotal support, of a brush rotating in said hopper, and pulleys or wheels, 95 one for driving the shaft on which the brush is journaled and one coincident with the pivotal support of the said hopper, substantially as specified.

2. The combination, with corrugating-dies 100 and ways or tracks, whereby the nails to be corrugated are conveyed toward the corrugating-dies, of a curved tube or chute for conveying the nails from the ways or tracks toward the corrugating-dies and presenting them in 105 an approximately horizontal position for entrance between the corrugating-dies, substantially as specified.

H. A. HARVEY.
